ABSTRACT OF THE DISCLOSURE

Lifting magnets having an intermediate pole of magnetizable material which is inserted between two coaxial magnetic coils. Each of the coils has substantially the identical number of ampere turns. The lifting magnet has a relatively high carrying capacity when the two coils are fed with current which permits the magnet to lift a single thin sheet from a stack of sheets of magnetizable material.

The invention relates to a lifting magnet for sheet-formed objects of magnetisable material and with at least one magnet coil which may be connected to a source of current and which is carried coaxially in a preferably circular cylindrical yoke having a flat underside with annular pole surfaces.

Lifting magnets of the aforesaid kind are known and they are used among other things for transporting sheets of magnetisable material such as mild steel by means of a magnet crane in which the lifting magnet is suspended. In that case it is advantageous if it is possible to transport partly a stack of such sheets, partly to lift a single thin sheet from such a stack. In the known lifting magnets the latter may take place, for example by first lifting a number of sheets from the stack, subsequently cutting off current to the magnet coil for brief intervals one or more times, as a consequence of which the lowermost sheets will be separated off, leaving ultimately only a single sheet adhering to the lifting magnet.

This known method of separating the sheets has, however, certain drawbacks; among other things, it is time-consuming, and the sheets may be damaged when falling. Further, a relatively extensive electronic equipment is required in automatic cranes to ensure satisfactory separation of the uppermost sheet from the remaining sheets of the stack, and in adjusting and operating this equipment special allowance has to be made for the thickness of the sheets.

Another known method consists in gradually reducing the terminal voltage to the magnet coils, by which a gradual reduction of the carrying capacity of the lifting magnet is obtained until it lifts a single sheet only. However, a substantial reduction of the terminal voltage to the magnet coils is required with consequent reduction of the resulting magnetic field in order to obtain a substantial reduction in the carrying capacity, and such a reduction in the terminal voltage supplied to the magnet coils involves a considerable factor of uncertainty, since the lines of force of the weakened field are distributed over the entire pole surface area and since the carrying capacity of the lifting magnet is inversely proportional with the pole surface area.

It is the object of the invention to devise a lifting magnet of the aforesaid kind having none of the drawbacks referred to, and an essential feature of a lifting magnet according to the invention is that an intermediate pole of magnetisable material which is common for the magnetic circuit of both of two coaxial magnet coils is inserted

2

between the said two coils, both of which are so dimensioned that, when connected to the source of current, each of them separately has substantially the identical number of ampere turns.

As a result, the lifting magnet will have a relatively high carrying capacity when the two coils are fed with current so that they produce magnetic fields with the same radial direction in the sheets adhering to the pole surface, the said fields being added to the resulting field which is of great strength and has a great capacity of penetrating into the sheets and extends outside the intermediate pole, but through the outer and inner pole of the magnet. If the direction of the current supplied to one coil is reversed, the two coils will produce magnetic fields of radially opposed directions in the sheets, and these fields will be subtracted to a resultant field having a lower strength and less capacity of penetrating into the sheets, the said field extending concentrated through the pole surface area of the intermediate pole and through the pole surfaces of the outer and the inner poles. The difference of the lines of force of the magnet fields in the two cases may be utilised, partly for carrying a whole stack of sheets of magnetisable material, partly for lifting only the uppermost thin sheet from the remaining sheets of the stack.

In one embodiment of the lifting magnet according to the invention the pole surface of the intermediate pole is of an area which is equal to one fourth of the area of each of the pole surfaces in the magnetic circuit which surrounds both the coils.

The invention will now be further described by way of example and with reference to the drawing, in which

FIG. 1 shows a diametrical section of an embodiment of a lifting magnet according to the invention and with an intermediate pole the pole surface area of which is equal to one fourth of the pole surface areas of the magnetic circuit which surrounds both magnet coils of the lifting magnet,

FIGS. 2—5 show diagrammatically magnetic circuits in same in four different combinations of the current supply to the magnet coils of the lifting magnet,

FIG. 6 shows curves of the carrying capacity W of the same lifting magnet as a function of the sheet thickness T when the magnet coils of the lifting magnet are fed with current as indicated in FIGS. 4 and 5, respectively, and

FIG. 7 shows curves for a force S as further described below, the said force being referred to as the separating force, at varying terminal voltage for the lifting magnet according to the invention, partly in cases where the lines of force of the magnetic fields are as indicated in FIG. 4, partly in cases where the lines of force of the magnetic fields are as indicated in FIG. 5.

The lifting magnet according to the invention as illustrated in FIG. 1 has two coaxial magnet coils, an inner coil 1 and an outer coil 2, each of which may be connected to a source of direct current (not shown) and carried in a preferably circular cylindrical yoke 3 of magnetisable material. The said yoke has a flat underside 4 with annular pole surfaces for an inner pole 5 and an outer pole 6. The lifting magnet has furthermore suspension means (not shown) connecting it to a hoisting mechanism or the lifting means of a magnet crane. According to the invention an intermediate pole 7 of magnetisable material is inserted between the two axial magnet coils 1 and 2, the said pole 7 being common for the magnetic circuits X and Y, respectively, of both coils and its magnetic cross-section Q_m being at right angles to the magnetic lines of field in the embodiment illustrated in FIGS. 1—5 substantially smaller than the cross-sections Q_i and Q_y of the magnetic circuit surrounding both of the coils 1 and 2. The magnet

coils 1 and 2 are so dimensioned that, when connected to the current source (not shown), each of them have substantially the identical number of ampere turns.

When a lifting magnet according to the invention and of the type shown in FIG. 1 is to be used to lift either a whole stack of sheets of magnetisable material or only the uppermost thin sheet of the stack, the depth of penetration of the magnetic fields into the object to be lifted has to be varied, and the said penetration depends upon the following three factors:

- (1) The magnetic resistance of the object to be lifted,
- (2) The flux produced by the magnet coils,
- (3) The area and shape of the pole surfaces.

The factor 1 will be fixed for each available object and cannot be altered.

The factor 2 can be varied within the range of zero to maximum by variation of the number of ampere turns of the magnet coils.

The factor 3 is fixed best possible by dimensioning the lifting magnet so as to obtain a maximum carrying capacity W in connection with a whole stack of sheets and an optimum separating force S, that is, the minimum force to be applied on a central pull to separate a thick sheet, corresponding to a stack of sheets, from an uppermost sheet lying in direct contact with the underside of the lifting magnet. A separating force is measured by means of a dynamometer, and the whole force includes the weight of the thick sheet.

The distribution of the magnetic flux in a lifting magnet as indicated in FIG. 1 is substantially determined by the size of the air gap between the underside of the magnet and the object, and if there is the identical size of the gap at all of the three pole surfaces when an object is resting in contact with the underside of the magnet, the magnetic resistances in the three air gaps at the outer pole, the intermediate pole and the inner pole will be approximately proportional with the area of the corresponding pole surface.

In one embodiment of the lifting magnet according to the invention the pole surface of the intermediate pole has an area equal to one-fourth of the pole surface areas of the magnetic circuit surrounding both magnet coils, by which a satisfactory proportion in practice between the carrying capacity W of the lifting magnet is obtained when the magnet coils 1 and 2 produce magnetic fields as indicated in FIG. 5 and the whole separating force S occurring when the two coils produce magnetic fields as indicated in FIG. 4.

FIGS. 2-5 show the distribution of field lines at various combinations of the current supply to the two magnet coils 1 and 2 provided, as indicated above, that the pole surface area Q_m of the intermediate pole is equal to one-fourth of the pole surface areas of the outer and inner pole, Q_y and Q_b , respectively.

With the directions of current, indicated by normal symbols in FIGS. 2-5, the pole surfaces will have the north and south poles indicated by N and S, the numerical values representing the relative flux distribution between the pole surfaces and a sheet-formed object 8 resting in contact with these, and it is a further prerequisite that the object is not magnetised beyond the limit of magnetic saturation of the material.

FIG. 2 shows poles and relative flux distribution when only the inner coil 1 receives current and produces a field X with a relative flux value of 5 in the sheet-formed object 8.

FIG. 3 shows poles and relative flux distribution when only the outer coil 2 receives current and produces a field Y, likewise with a relative flux value of 5, in the sheet-formed object 8.

FIG. 4 shows poles and relative flux distribution when both the inner coil 1 and the outer coil 2 receive current so that the fields produced, X' and Y', produce a relatively weak field X'-Y' with a relative flux value of 1 in the sheet-formed object 8.

FIG. 5 shows poles and relative distribution of flux when both the inner coil 1 and the outer coil 2 receive current so that the resulting fields X'' and Y'' as a result produce a relatively strong field X''+Y'' with a relative flux value 9 in the sheet-formed object 8.

On comparing FIGS. 4 and 5, it will be seen that in the first case the resulting field in the intermediate pole 7 has a value of two relative units, and that the field X'+Y' extends through the intermediate pole 7, which has a south pole at its pole surface, whereas the inner pole and the outer pole has a north pole at their pole surfaces.

In the second case (FIG. 5) the resulting field is of nine relative units in the outer and inner poles, and it extends between the outer pole 6, which is a north pole, and the inner pole 5, which is a south pole, whereas the two fields X''-Y'' anyway approximately will eliminate each other in the intermediate pole 7.

The carrying capacity W of the lifting magnet may, as is known, be calculated with substantial approximation out from the formula:

$$W = \frac{\phi^2}{9.81\mu a} = \text{constant} \frac{\phi^2}{a} \text{ kg.}$$

(a) If this formula is applied to the case of FIG. 4, the result arrived at will be a total relative carrying capacity $W=1^2/1+2^2/4+1^2/1=18$ relative units of force.

(b) If the intermediate pole 7 is omitted and the terminal voltage of the two magnet coils is reduced so that the flux values constitute a relative unit both in the outer pole 6 and in the inner pole 5, we have: $W=1^2/1+1^2/1=2$ relative units of force, which shows that for the same relative magnetic field in the sheet 8 to be lifted a ninefold carrying capacity of the lifting magnet will be obtained by providing the lifting magnet according to the invention with an intermediate pole 7.

(c) If the formula is applied to the case according to FIG. 5, the relative carrying capacity obtained in the magnet will be:

$W=9^2/1+9^2/1=162$ relative units of force, which means a ninefold carrying capacity of the lifting magnet in the case illustrated in FIG. 5 compared with the case illustrated in FIG. 4.

(d) If the intermediate pole is omitted in the case of FIG. 5, this will not have any appreciable influence upon the carrying capacity W of the lifting magnet, which has been confirmed by tests, and this is due to the fact that the fields of the intermediate pole 7 eliminate each other as indicated in FIG. 5.

The conclusion derived thereby is that by reversing the current of magnetisation in one of the magnet coils 1 or 2 of the lifting magnet according to the invention, that is, from the case illustrated in FIG. 5 to the case illustrated in FIG. 4, the carrying capacity W of the lifting magnet will be changed from 162 to 18 relative units of force.

In the case illustrated in FIG. 4 the relative flux value in the sheet-formed object 8 will be a relative unit, and this means that the fields are so relatively small that their lines of force extend essentially in the uppermost sheet which is retained to the lifting magnet by eighteen relative units of force, calculated under (a), and the fields do not penetrate to any appreciable depth into the underlying sheet.

If the intermediate pole 7 is omitted, that is, as in the known lifting magnets, a regulated reduction of the terminal voltage of the lifting magnet until the relative flux value of outer poles and inner pole is equal to one relative unit, the uppermost sheet of a stack will only be retained by two relative units of force as indicated under (b), that is, by only one ninth of the force produced in the lifting magnet according to the invention, there is thus a considerably greater risk of the uppermost sheet of the stack not being retained, but, on the con-

trary, the said sheet will fall simultaneously with the remaining part of the stack.

The above theoretical calculations have been confirmed by tests, the results of which are indicated in the graphs 6 and 7.

FIG. 6 shows curves of values measured of the carrying capacity W of a convenient embodiment of the lifting magnet described above by way of example as used in connection with various sheet thicknesses T , and it may be added that a lifting magnet of the same type, but without intermediate pole has under the same conditions and with the magnet coils 1 and 2 fed with current as indicated in FIG. 5 a maximum carrying capacity of about 2500 kg. at a sheet thickness of 50 mm., the carrying capacity varying with the sheet thickness as indicated by a curve A.

Another curve B shows that the lifting magnet according to the invention has a maximum carrying capacity about 10% less, that is about 2200 kg. at a sheet thickness of 50 mm., than a lifting magnet without intermediate pole (Curve A). The lifting magnet according to the invention has as shown by a curve C a carrying capacity of about 200 kg. when the magnet coils 1 and 2 are fed with current as indicated in FIG. 4. The curve C further shows that the carrying capacity in the case of FIG. 4 is rather independent of the sheet thickness.

FIG. 7 shows curves measured for the separating force S of a lifting magnet according to the invention at a constant direct voltage of 110 volts as a function of the thickness of the uppermost sheet. A curve D shows that at the said direct voltage and a magnetisation of the lifting magnet corresponding to FIG. 5 the separating force S will be below 50 kg. when the sheet thickness T is greater than 15 mm. If, however, the sheet thickness is less than 15 mm. and the magnetisation is as indicated in FIG. 4, a substantially larger separating force is required, that is, as far as up to 550 kg. and 850 kg. in the case of sheet thicknesses T , 5 and 3 mm., respectively. Whether in such case more than a single sheet will be lifted, will thus depend on the length and width of the sheet, since the sheet lying beneath the first one will be carried with if its weight is less than 550 kg. and 850 kg., respectively. By means of a lifting magnet according to the invention the separating force will, however, as shown by a curve E, with the two magnet coils connected as indicated in FIG. 4, be very low, since

even in the case of a 3 mm. sheet the separating force required will only be 30 kg., that is, a 3 mm. sheet of about 1.3 m.² may be separated from another sheet of any thickness whatever or from a stack of any size whatever consisting of 3 mm. sheets.

Corresponding tests with a lifting magnet without intermediate pole, that is, like the known lifting magnets, have disclosed that the voltage to the magnet coils has to be reduced to substantially less than 20 volts in order to obtain a separating force S in the case of a 3 mm. sheet for less than 100 kg., but simultaneously the carrying capacity W will only be about 50 kg. at 20 volts, and the known lifting magnet will thus drop the stack of sheets before the uppermost 3 mm. sheet is separated from the stack.

What we claim is:

1. A lifting magnet for sheet-formed objects of magnetizable material and with at least one magnet coil which may be connected to a source of current and which is carried coaxially in a preferably circular cylindrical yoke having a flat underside with annular pole surfaces, characterized in that an intermediate pole of magnetizable material which is common for the magnetic circuit of both of two coaxial magnet coils is inserted between the said two coils, both of which are so dimensioned that, when connected to the source of current, each of them separately has substantially the identical number of ampere turns.

2. A lifting magnet as claimed in claim 1, characterized in that the pole surface of the intermediate pole is of an area which is equal to one fourth of the area of each of the pole surfaces in the magnetic circuit which surrounds both the magnet coils.
